US0D1049170S

(12) **United States Design Patent** (10) Patent No.: **US D1,049,170 S**
(45) Date of Patent: ** Oct. 29, 2024

(54) **COMPRESSOR WITH INTEGRATED ELECTROMOTOR**

(71) Applicant: **INNOMOTICS GMBH**, Nuremberg (DE)

(72) Inventors: **Klaus Büttner**, Hollstadt (DE); **Klaus Kirchner**, Ostheim (DE); **Matthias Warmuth**, Windshausen (DE)

(73) Assignee: **Innomotics GmbH**, Nuremberg (DE)

(**) Term: **15 Years**

(21) Appl. No.: **29/733,936**

(22) Filed: **May 7, 2020**

Related U.S. Application Data

(62) Division of application No. 29/649,651, filed on May 31, 2018, now Pat. No. Des. 886,873.

(57) **CLAIM**

The ornamental design for a compressor with integrated electromotor, as shown and described.

DESCRIPTION

FIG. 1 is a front view of a compressor with integrated electromotor, showing our new design;

FIG. 2 is a rear view thereof;

FIG. 3 is a top view thereof;

FIG. 4 is a bottom view thereof;

FIG. 5 is a right side view thereof;

FIG. 6 is a left side view thereof; and,

FIG. 7 is a front, top and right side perspective view thereof.

The broken lines constituting various features in the drawings form no part of the claimed design.
